(57) **CLAIM**

The ornamental design for a cutting insert, as shown and described.

DESCRIPTION

FIG. 1 is a top perspective view of a cutting insert showing my new design;

FIG. 2 is a right-side elevation view thereof;

FIG. 3 is a left-side elevation view thereof;

FIG. 4 is a rear elevation view thereof;

FIG. 5 is a front elevation view thereof;

FIG. 6 is a top plan view thereof;

FIG. 7 is a bottom plan view thereof; and,

FIG. 8 is a top perspective view of the cutting insert of FIGS. 1-7 installed into a cutting tool or tool holder, which is illustrated along with a second cutting insert installed into the cutting tool or tool holder to provide example environment.

The broken line showing of the cutting tool or tool holder and the second cutting insert in FIG. 8 is for the purpose of illustrating environmental structure that forms no part of the claimed design.
